UNITED STATES PATENT OFFICE.

JOHN SHANKS, OF BARRHEAD, SCOTLAND.

DESIGN FOR A URINAL.

45,207.

Specification for Design.

Patented Feb. 3, 1914.

Application filed October 4, 1913. Serial No. 793,491. Term of patent 7 years.

To all whom it may concern:

Be it known that I, JOHN SHANKS, a subject of the King of the United Kingdom of Great Britain and Ireland, residing at Barrhead, Renfrewshire, Scotland, have invented a new, original, and ornamental Design for a Urinal, of which the following is a specification, reference being had to the accompanying drawing, forming part thereof.

The accompanying drawing is a perspective view of a urinal, showing my new design.

I claim:

The ornamental design for a urinal, as shown.

In testimony whereof I have signed my name to this specification in the presence of two subscribing witnesses.

JOHN SHANKS.
